UNITED STATES PATENT OFFICE.

CHARLES A. ELB, OF NEW BRUNSWICK, NEW JERSEY.

AUTOMATIC TRAIN-STOP.

1,136,944.

Specification of Letters Patent. Patented Apr. 27, 1915.

Application filed October 8, 1913. Serial No. 794,107.

To all whom it may concern:

Be it known that I, CHARLES A. ELB, a citizen of the United States, residing at New Brunswick, in the county of Middlesex and State of New Jersey, have invented a new and useful Automatic Train-Stop, of which the following is a specification.

The invention relates to improvements in automatic train stops.

The object of the present invention is to improve the construction of automatic train stops, and to provide a simple, practical and efficient train stop of strong and durable construction adapted to be easily applied to modern high speed compound locomotives and other engines, and designed to be operated either independently of or in conjunction with the usual train signals, and capable should an engineer attempt to pass a signal set against him of cutting off the steam of the engine and applying the brakes, whereby the train will be brought to a standstill.

A further object of the invention is to provide an automatic train stop of this character, which will be beyond the control of the engineer and which after an operation will require an engineer to leave his cab and manually reset the mechanism.

Another object of the invention is to provide an automatic train stop equipped with a track device, which will effectually prevent unauthorized persons from surreptitiously moving it to its engaging position for stopping a train.

With these and other objects in view, the invention consists in the construction and novel combination of parts hereinafter fully described, illustrated in the accompanying drawings, and pointed out in the claims hereto appended; it being understood that various changes in the form, proportion, size and minor details of construction, within the scope of the claims, may be resorted to without departing from the spirit or sacrificing any of the advantages of the invention.

In the drawings:—Figure 1 is a side elevation of a portion of a locomotive equipped with an automatic train stop, constructed in accordance with this invention. Fig. 2 is a transverse sectional view of the same. Fig. 3 is an enlarged vertical sectional view of a portion of the automatic train stop, illustrating the construction of the cylinder, the shoe for actuating the controlling valve and

showing the track device in its raised position. Fig. 4 is an enlarged vertical sectional view of the track device.

Like numerals of reference designate corresponding parts in all the figures of the drawings.

In the accompanying drawings in which is illustrated the preferred embodiment of the invention, the automatic train stop comprises in its construction a steam cylinder 1 preferably mounted in a vertical position beneath the boiler 2 of a locomotive and bolted or otherwise secured to a transverse supporting sheet 3. The supporting sheet 3 is attached to and depends from the bottom of the boiler, but the steam cylinder may be mounted and arranged in any other preferred manner. The steam cylinder has a vertically movable piston 4 provided with a piston rod 5 extending upwardly through a stuffing box 6 at the top of the cylinder and connected with a brake operating lever 7 and with valves 8 and 9 arranged to cut off the flow of steam from the boiler to the cylinders of the locomotive to stop the operation of the latter simultaneously with an application of the air brakes. The lever 7, which is arranged in a horizontal position when the piston is at the lower limit of its travel, is pivoted at its front end 10 to the upper end of a vertical supporting arm 11 and is suitably connected at an intermediate point with the piston rod to permit a pivotal movement of the parts, and its rear end is provided with an eye 12 to which is secured one end of an operating cord 13, extending downwardly from the lever 7 and passing around the guide pulley 14 and designed to extend to and connected with a suitable valve for reducing the pressure in the train pipe for effecting an operation of the brakes.

Any suitable air valve may be employed for bleeding the train pipe of the air brake system, and as the present invention is applicable to various forms of valves, a detail description and illustration of a particular type of air valve is deemed unnecessary. The supporting arm is suitably secured to the steam cylinder at the top thereof and projects upwardly therefrom. The guide pulley 14 is mounted in a bifurcation of a horizontal supporting arm or bracket 15, which is suitably secured to the rear face of the supporting sheet 3.

The upper end of the piston is connected by a bolt 16 or other suitable pivot to the

inner end of a transversely disposed lever 17 fulcrumed at an intermediate point to a fixed supporting arm 18 by a suitable pivot 19 and connected at its outer terminal to the rear end of a horizontal arm of a bell crank lever 20. The supporting arm 18 is secured to the boiler of the locomotive at one side thereof and extends downwardly therefrom, as clearly shown in Fig. 2 of the drawings, and the bell crank lever, which is fulcrumed at its angle on a suitable pivot 21, has an upwardly extending arm 22 arranged in approximately a vertical position and provided with a slot 23 in which operates a suitable pin or pivot 24 for connecting the bell crank lever with a depending arm 25 of a valve rod or stem 26. The valve or stem is provided with an outer extension, to which the said depending arm 25 is secured.

20 The bell crank lever is supported by an approximately U-shaped bracket 27 secured to the locomotive at one side thereof and having the said pivot 21 mounted on its outer portion. Any other suitable means 25 may, of course, be employed for mounting the bell crank lever, and in practice the connections between the steam cylinder 1 and the valve or valves of the steam conduit 28 of the locomotive will be mounted and arranged to suit the type of locomotive to which the automatic train pipe is applied. In the locomotive illustrated in the accompanying drawings, the steam conduit 28 is provided at the front with two branches 29 leading to the steam cylinders at opposite sides of the locomotive, the valves 8 and 9 being necessary to cut off the flow of steam to both sets of cylinders of the locomotive. In any type of engine where a portion of 30 the steam conduit 28 is directly accessible, a single valve may be employed for cutting off the steam from the boiler to the cylinders. The valves 8 and 9, which are located at opposite sides of the locomotive, are straight- 35 way shut off valves, but any other type of valve may be employed. These valves 8 and 9 are provided with transversely aligned valve plugs having stems 30 and 31 detachably connected at their adjacent ends by a 40 suitable coupling 32 consisting of a socket and a removable coupling pin or key 33 and adapted to permit the valve stems to be separated when it is desired to remove the valve plugs. The socket of the coupling has a 45 rectangular opening and the stem 31 is squared to fit the same so that when the arm 25, which is connected with the stem 30 is oscillated, the valve plugs will be simultaneously actuated to open or close the valves 50 8 and 9.

55 The steam cylinder has a steam chest 34 and is provided with upper and lower feed and exhaust passages 35 and 36, which are controlled by a slide valve 37 adapted to 60 connect the feed or inlet passage at one end of the cylinder with the steam chest and the exhaust passage of the other end of the cylinder with an exhaust chamber or escape 38, while closing the other passages. When the slide valve is at the downward limit of its travel, as illustrated in Fig. 3 of the drawings, the piston 4 is at the lower end of the cylinder being maintained in such position by steam pressure. Steam from the boiler to the locomotive is admitted to the steam chest 34 by a pipe 39 extending from the upper end of the steam chest to the pipe 40, which supplies steam to the air pump or compressor 41 of the locomotive. This arrangement forms a convenient means for 65 maintaining a constant steam pressure in the steam cylinder 1, but the locomotive may be tapped at any other suitable point to obtain the necessary pressure for operating the piston. When the slide valve is moved 70 from its lower position to its upper position, steam is admitted to the lower end of the cylinder 1 and the upper end of the cylinder is connected with the exhaust chamber and the piston 4 is caused to travel upwardly, 75 thereby oscillating the brake operating lever 7 and simultaneously transmitting motion to the bell crank lever, which closes the valves and cuts off the supply of steam to the cylinders of the engine.

80 The slide valve is connected with a depending rod or stem 41^a, extending through a stuffing box 42 at the lower end of the steam chest and guided in an arm 43 of a bracket 44 and yieldably connected with the shoe 45 adapted to be actuated by a track device 46. The slide valve is preferably supported in its lower position by a set collar 47 mounted on the valve rod or stem and arranged to rest upon the lower end of the steam chest. The upper terminal portion 48 of the valve rod or stem is threaded and is secured in openings of projecting ears 49 of the slide valve by nuts 50. The supporting bracket consists of a depending arm provided at the upper end with an attaching portion 51, which is bolted or otherwise secured to the lower end of the steam cylinder 1, but it may be mounted on the locomotive in any other desired manner. The 100 supporting bracket is provided at the bottom with a straight depending supporting portion 52, extending below the horizontal guide arm 43 and bifurcated to receive one end of the shoe 45, which is connected to the bracket 105 by a pivot 53. The shoe, which is curved longitudinally to present a lower convex surface, is provided at a point intermediate of its ends with an upwardly projecting lug 54, which is pivoted by a bolt or rivet 55 110 in the lower bifurcated end of the vertical sleeve 56, slidably mounted on the lower end of the valve rod or stem 41^a and receiving a coiled spring 57 interposed between the shoe 115 and the valve stem to cushion the former and 120

125 130

enable the mechanism carried by the locomotive to contact with the track device 46 without injury even when the train is traveling at a relatively high rate of speed. The sleeve 56 is provided at opposite sides with longitudinal slots 58 into which extends the terminal portions of a transverse pin 59 piercing the valve rod or stem and projecting from opposite sides thereof.

10 The track device 46 comprises a vertically movable plunger 60, provided at its upper end with a rounded transversely disposed head, and operating in a vertical cylinder 61 having an attaching portion 62 at its lower end and suitably secured between the rails 15 preferably at the central portion of the track, as illustrated in Fig. 2 of the drawings, but the track device and the cylinder 1 may be located at one side of the track so that a separate set of signals and track devices 20 may be arranged at each side of a single track for controlling trains traveling thereon in opposite directions. The vertical cylinder 61 is connected at the bottom by a pipe 63 with a suitable source of air supply, preferably the pipe lines, for operating a semaphore or other signal and when pressure is introduced into the lower end of the cylinder 61, the plunger 60 is forced upwardly to its elevated or engaging position 25 in the path of the shoe 45. When the air is exhausted, the plunger descends by gravity assisted by coiled springs 64, mounted on the lower portions of spaced vertical rods 65 secured at their upper ends to the transverse 30 head of the plunger 60 and extending downwardly therefrom through openings in horizontal guiding arms 66, preferably formed integral with and extending from opposite sides of the cylinder 61 at the upper portion 35 thereof, as clearly illustrated in Fig. 4 of the drawings. The upper ends of the slideable rods 65 are preferably threaded in perforations of the cross head of the plunger, and the lower terminals of the said rod are 40 threaded for the reception of nuts 67, arranged in pairs and supporting the coiled springs 64, which are interposed between the said nuts and the fixed horizontal guiding arms 66. The plunger 60 is provided at its 45 lower portion with suitable packing rings and in practice suction will effectually prevent the plunger from being surreptitiously lifted by unauthorized persons when the air is cut off, so that it will be impossible for 50 such persons to stop a train by moving a track device from its lower to its elevated or engaging position. No claim is made in the present application to the track device. 55 When the mechanism carried by a train engages and is operated by the track device, the brakes are applied and the steam is cut off from the cylinders of the engine, and it is necessary after the train stops for the 60 engineer to descend from the cab and swing 65

the shoe downwardly from its elevated position to its lowered position. This changes the position of the slide valve and admits steam to the upper end of the cylinder 1 and exhausts steam from the lower end of the cylinder, thereby returning the brake operating lever and the valves 8 and 9 to their normal positions. The valves 8 and 9, which control the supply of steam from the boiler to the cylinder, are independent of the throttle valve and are located interiorly of the locomotive between the throttle valve and the cylinders of the engine, and the said valves are beyond the control of the engineer so that it is impossible for the latter to interfere with the operation of the automatic train stop. Instead of connecting the pipe line 39 with the pipe 40 or other steam supply pipe of the locomotive, it may be connected with the air tank and the piston 4 operated by compressed air.

What is claimed is:—

1. In an automatic train stop, the combination with a locomotive, of a steam controlling valve mounted in the main steam conduit of the locomotive at a point between the throttle valve and the cylinders for cutting off the steam, a cylinder located beneath the locomotive and having a piston, lever connections between the piston and the steam valve, a reciprocating valve mounted on the cylinder and having a depending vertical stem, and a shoe connected to the stem and arranged to be operated by a track device. 95

2. In an automatic train stop, the combination with a locomotive, of a steam controlling valve mounted in the main conduit of the locomotive at a point between the throttle valve and the steam cylinders for cutting off the steam, a vertical cylinder located beneath the locomotive and having a vertically movable piston, mechanical means for connecting the piston with the steam controlling valve for actuating the latter, a vertically movable reciprocating valve mounted on the cylinder and having a depending stem, and a shoe connected to the stem and arranged to be actuated by a track device. 100 105 110

3. In an automatic train stop, the combination with a locomotive having a main steam conduit provided with branches extending to opposite sides of the locomotive, of steam controlling valves mounted in the said branches and located at points between the throttle valve and the cylinders, said valves being provided with means extending across the locomotive for connecting them and causing the valves to operate in unison, an arm connected with one of the valves, a bell crank lever fulcrumed at its angle and having one of its arms connected to the arm of the valve, a cylinder having a piston connected with the other arm of the bell crank lever, a track device, and means carried by the locomotive and ar- 130

ranged in the path of and adapted to be actuated by the track device for controlling the flow of fluid pressure to and from the last-mentioned cylinder.

5. In an automatic train stop, the combination with a locomotive, of a steam controlling valve mounted in the main steam conduit of the locomotive at a point beyond the throttle valve, a vertical cylinder car-

ried by the locomotive and located beneath the boiler and having a piston, a transverse lever fulcrumed at an intermediate point and connected at its inner end with the piston, a bell crank lever arranged at one side of the locomotive and having an arm connected with the steam controlling valve, means for connecting the other arm of the bell crank lever with the outer arm of the transverse lever, a track device, and means carried by the locomotive and arranged in the path of and adapted to be actuated by the track device for controlling the flow of fluid pressure to and from the cylinder.

5. In an automatic train stop, the combination with a locomotive, of a steam controlling valve mounted in the main steam conduit of the locomotive at a point beyond the throttle valve, a cylinder located beneath the locomotive and having a piston connected with the steam controlling valve for actuating the same, a reciprocatory valve mounted on the cylinder and having a depending stem, and a curved shoe pivotally mounted at one end and connected 35 to the valve stem, said shoe presenting a lower convex face and adapted to be actuated by a track device.

6. In an automatic train stop, the combination with a locomotive, of a steam controlling valve mounted in the main steam conduit of the locomotive at a point beyond the throttle valve, a cylinder located beneath the locomotive and having a piston connected with the steam controlling valve for 45 actuating the same, a reciprocatory valve mounted on the cylinder and having a depending stem, a pivotally mounted shoe located beneath the valve stem, and yieldable means including a cushioning spring 50 for connecting the shoe to the rod or stem.

7. In an automatic train stop, the combination with a locomotive, of a steam controlling valve mounted in the main steam conduit of the locomotive at a point beyond 55 the throttle valve, a vertical cylinder hav-

ing a piston connected with the steam controlling valve, a reciprocatory valve controlling admission of fluid pressure to the cylinder and provided with a depending stem, a bracket secured to and depending from the cylinder, and a shoe pivotally mounted on the bracket and connected to the stem, said shoe being arranged to be actuated by a track device.

8. An automatic train stop including a vertical cylinder having a piston, a valve controlling the admission of fluid pressure to the cylinder, a vertical rod or stem connected with the valve, a bracket secured to and depending from the cylinder and having means for guiding the rod or stem, and a shoe pivotally mounted on the bracket and connected with the rod or stem and adapted to be actuated by a track device.

9. An automatic train stop including a vertical cylinder having a piston, a valve controlling the admission of fluid pressure to the cylinder, a vertical rod or stem connected with the valve, a bracket secured to the lower end of the cylinder and provided at an intermediate point with a horizontal guide arm receiving the rod or stem, said bracket being also provided with a lower supporting portion projecting below the said arm, and a shoe pivoted to the supporting portion and connected with the rod or stem.

10. In an automatic train stop, the combination with a locomotive, of a steam controlling valve mounted in the main steam conduit beyond the throttle valve, a cylinder having a piston operating in the cylinder and provided with a piston rod, a pair of levers connected directly with and actuated by the piston rod, one of the levers being designed to be connected with an air brake valve, means for connecting the other lever with the steam controlling valve, a reciprocatory valve mounted on the cylinder and having a depending stem, and a shoe connected to the stem and arranged to be actuated by a track device.

In testimony, that I claim the foregoing as my own, I have hereto affixed my signature in the presence of two witnesses.
